[57] ABSTRACT

Safety apparatus to protect against failure of a winch
cable in lowering a tower mounted light fixture frame
normally suspended by several suspension cables ex-
tending downwardly through the tower, including a
pair of stationary cables in the tower and extending
from bottom to top; a safety appliance sliding along
such safety and guide cables and interconnecting the
suspension cables to the winch cable and including a
friction gripping mechanism sliding along one of the
safety cables and normally held out of locked condi-
tion by the tension load transmitted between the
winch cable and the suspension cables; and including
spring connections between the safety appliance and
the winch and suspension cables.

SAFETY APPARATUS FOR LOWERING TOWER EQUIPMENT

BACKGROUND OF THE INVENTION

In illuminating highway intersections and other larger spaces such as parking lots, it has been found desirable to use towers which are quite high, from 90 to 150 feet or more in height. By use of towers of such height, the number of towers needed to illuminate a large area is considerably reduced. The actual lamps are carried on a fixture frame which is suspended by cables from pulleys at the top of the tower and may be lowered to the ground so that the lamps may be easily serviced. Lowering the fixture frame and lamps to the ground is an alternative to having a workman climb to the top of the tower to service the lamps.

Of course, by allowing the workman to remain on the ground and by lowering the fixture frame and lamps to the ground, the likelihood of injury to the workman is materially reduced. However, there is some inherent danger in lowering such fixture frames and lamps from high elevations to the ground, because there is always the possibility of breakage or rupture of a winch cable which is used for lowering the fixture frame and lamps to the ground.

In the ordinary construction of the tower, there are several pulleys provided at the top of the tower and several suspension cables which function to continuously suspend the fixture frame and hold it upwardly against rigid crossarms at the top of the tower. The suspension cables extend down through the tower and are normally attached to a counterweight at the bottom of the tower so that tension on the suspension cables is maintained at all times.

When the fixture frame is to be lowered, a winch is inserted between the counterweight and the suspension cables, and, as the winch cable is payed out, the counterweight will first be lowered onto a solid rest at the bottom of the tower and then the suspension cables are allowed to move upwardly through the tower and then over the pulleys for allowing the fixture frame to be lowered at the outside of the tower.

Several suspension cables are utilized so that the fixture frame is balanced, and is prevented from swaying due to wind, and the use of several substantially parallel suspension cables prevents any possibility of allowing the fixture frame and the lamps to drop due to rupture of a suspension cable because there are always several suspension cables which can independently support the fixture frame.

However, only one winch cable is ordinarily utilized during lowering of the fixture frame and if such a winch cable were to fail during lowering of the fixture frame, a great deal of damage could occur.

BRIEF SUMMARY OF THE INVENTION

Accordingly, the present invention is addressed to preventing or minimizing the likelihood of any damage occurring in the event that the winch cable should fail during lowering of the fixture frame along a high tower.

The present invention constitutes safety apparatus to be mounted in a tower and utilized in connection with the winch cable so as to immediately assume the weight of the fixture frame and hold the fixture frame in the event that the winch cable should fail.

The present invention utilizes a pair of guide cables in the tower which are anchored at both the top and bottom ends. A safety appliance is connected to the suspension cables and is also connected to the winch cable for transmitting the tension load between the winch cable and the suspension cables during lowering of the fixture frame. The safety appliance also guides along the large electrical cable, one end of which is attached to the fixture frame for supplying electrical energy to the lamps on the fixture frame, and the other end of the cable is ordinarily connected to a power source at the bottom of the tower, but is disconnected and moved upwardly in the tower with the suspension cables during such time as the fixture frame is being lowered.

The appliance incorporates a quick setting clamp to grip one of the solidly anchored guide cables in the tower in the event of a rupture or failure of the winch cable so that the appliance is securely anchored at a fixed location in the tower and the fixture frame is prevented from dropping freely. The suspension cables are connected to the appliance by spring connections so that when the appliance suddenly grips the guide cable in the tower, the tension load is applied to the suspension cables quickly, but not absolutely instantaneously, and therefore the suspension cables are prevented from snapping due to rapid application of load.

The clamping shoe is moved into locking engagement with the guide cable by a spring which is released upon failure of the winch cable, and the spring causes the clamping shoe to very rapidly grip the guide cable but does not cause the appliance to stop absolutely instantaneously on the guide cable (not as a pawl would stop against a ratchet tooth), to at least slightly lessen the rate of application of the load to the guide cable.

BRIEF DESCRIPTION OF THE DRAWINGS

FIG. 1 is an elevation view partly broken away and partly in section and illustrating use of the invention in connection with a light tower.

FIG. 2 is an enlarged detail perspective view of the safety apparatus, partly broken away for clarity of detail.

FIG. 3 is an enlarged detail transverse section view taken approximately at 3-3 in FIG. 2.

FIG. 4 is an enlarged detail section view taken approximately at 4-4 in FIG. 3.

DETAILED DESCRIPTION OF THE INVENTION

One form of the invention is illustrated in the drawings and is described herein.

The safety apparatus comprising the present invention is indicated in general by numeral 10 and is intended for use within the tubular pole 11 for supporting lamps 12 mounted on a fixture frame 13 which is normally disposed at the top of the tower but which may be lowered on its suspension cables 14 to the ground for servicing the lamps 12. This lighting tower is particularly designed for use in illuminating highway traffic interchanges and intersections, large parking areas and the like. The pole 11 may be 150 feet high or higher. The pole 11 has crossarms 15 projecting outwardly from its top, and pulleys are mounted at the top of the pole 11 and in the arms 15 for guiding the suspension cables 14 from within the tubular pole 11 to the fixture frame 13.

In the normal condition of the tower, the suspension cables 14 are entirely confined within the tubular pole 11 and the crossarms 15, and the suspension cables 14 serve to carry a counterweight 16 which more than offsets the weight of fixture frame 13 and lamps 12 so as to pull the fixture frame tightly up against the crossarms 15. As illustrated in FIG. 1, the counterweight 16 has a winch 17 affixed on its top, and the winch 17 has a winch cable 18 to carry the same tension load carried by the several suspension cables 14. Normally the counterweight 16 is suspended by the cables and off the base of structure of the tower. When the fixture frame 13 is to be lowered, the winch 17 will pay out the cable 18 and the first effect of this is to lower the counterweight 16 to the base of the tower which will thereafter support the counterweight. Subsequent operation of the winch 17 pays out additional cable to effect the lowering of the fixture frame 13.

The safety apparatus 10 includes a pair of safety and guide cables 19 and 20, and a safety appliance which is indicated in general by numeral 21 for interconnecting the suspension cables 14 and the winch cable 18 and transmitting the tension load therebetween. Normally the safety appliance 21 will slide freely along the guide and safety cables 19, 20, which are affixedly anchored to the tower at its bottom and top and are stationary within the pole 11. In the event that the winch cable 18 should fail, the safety appliance 21 will immediately clamp onto the safety cable 19 and will stop to prevent any uncontrolled travel of the suspension cable 14 upwardly through the pole 11 and falling of the fixture frame 13 and lamps 12 is thereby prevented.

The safety appliance 21 includes a pair of upper and lower rigid frame plates 22 and 23 which are rigidly interconnected by a pair of posts 24 and 25 which are welded to the upper and lower frame plates. The frame plates have rather large aligned openings 22.1 and 23.1 for receiving and retaining a multiple conductor electrical cable 26 which extends entirely to the top of the tower and supplies power to the lamps 12.

The frame plates also have aligned bearing or guide apertures or openings 22.2, 23.2 which receive and freely pass the guide and safety cables 19, 20 and maintain these cables in side by side relation.

The safety appliance 21 makes provision for a resiliently yieldable connection to each of the suspension cables 14, and accordingly, a plurality of rigid slide bars 27 are slidably mounted in openings 22.3 in the upper frame plate 22. These openings 22.3 are symmetrically and uniformly disposed around the periphery of the frame plate 22 for equal distribution of the load onto the frame plate from the suspension cables 14. The upper ends of the slide rods 27 are secured to connector fittings 14.1 on the ends of cables 14 by bolts 27.1.

The lower portions of the slide rods 27 below the frame plate 22 have compression springs 28 thereon. The springs 28 bear upwardly against the frame plate 22 and urge the slide rods 27 downwardly and bear against washers 27.2 and threaded nuts 27.3 threaded onto the lower ends of the rods 27.

A slide bar or rod 29 is provided for connecting to the winch cable 18 and is slidably mounted in an oblong shaped opening 23.3 in the lower frame plate 23. The opening 23.3 is located at the center of frame plate 23 and is oriented with the longest dimension of the oblong opening extending substantially toward the

guide and safety cable 19 and the opening 23.2 through which it extends so as to permit limited movement of the rod 29 toward and away from the guide and safety cable 19. The lower end of the slide bar 29 is connected to a fitting 18.1 on the end of cable 18 by means of a pin or bolt 29.1. A portion of the slide rod or bar 29 is disposed above the lower frame plate 23, and this upper portion of the rod 29 is encompassed by a compression spring 30 which bears downwardly against the frame plate 23 and bears upwardly against the bifurcated head 29.2 which is affixed on the upper end of rod 29. The spring therefore urges the rod 29 upwardly against the tension exerted by the winch cable 18, and as illustrated, the spring 30 is ordinarily compressed so that the convolutions of the spring bear against each other when the appliance 21 bears the tension load between winch cable 18 and the suspension cables 14.

A rigid U-shaped clamp body 31 is formed of heavy gauge steel and is affixed as by welding to the upper and lower frame plates 22 and 23 with the closed side 31.1 of the U-shape located adjacent the peripheries of the frame plates and defining a cable-guiding passage 31.2 confining the guide and safety cable 19 and extending between the apertures 22.2 and 23.2 in the frame plates and which guide the cable 19. The U-shaped clamp body 31 has its open side facing the rod 29 to receive clamp bar 32 therein. Clamp bar 32 is mounted on pivot 33 which is carried in apertures in the side plates 31.3 of the clamp body 31. The clamp bar 32 extends out of the open side of clamp body 31 and has its attachment end 32.1 connected by pivot 29.3 to the bifurcated head 29.2 of the slide bar or rod 29. The inner end of clamp bar 32 defines a clamping shoe 32.3 which is rounded and which is knurled or roughened in confronting relation with the cable 19 and the cable-guiding passage 31.2 of the clamp body 31. The inner end of the clamp bar extends obliquely toward the cable 19 and somewhat upwardly whereby upward swinging of the inner end of clamp bar 32 will cause the clamping shoe 32.3 to swing away from the cable 19, and downward swinging of the shoe 32.3 will cause it to engage and clamp against the cable 19.

The closed side 31.1 of the U-shaped clamp body 31 defines a clamping jaw, along the passage 31.2, which cooperates with the clamping shoe 32.3 of the clamp bar to grip the cable 19 and prevent upward movement of the appliance 21 along the cables.

Normally, while the light fixture frame 13 and lamps 12 are disposed at the top of the tower, the safety appliance 21 is located at the bottom of the pole 11, substantially as illustrated in FIG. 1. The tension load from the suspension cables 14 is translated to the winch cable 18 by the safety appliance 21. In this condition, the spring 30 will be substantially completely compressed so that the convolutions of the spring will bear against each other; and in this condition, the rod 29 will have pulled the end of clamp bar 32 downwardly so that the clamping shoe 32.3 will have swung upwardly away from the cable 19. Therefore there is no interference to sliding by the appliance along the cables 19 in the event that the winch 17 is operated to pay out the winch cable 18.

While the safety appliance 21 is in stationary condition at the bottom of the pole 11, the springs 28 on the slide rods 27 which serve to connect the suspension cables 14 to the appliance frame, are substantially completely compressed.

When the lamps 12 and the fixture frame 13 are to be lowered to the ground for service, the electric supply cable 26 may be disconnected from the power source near the bottom of pole 11 and then the winch 17 will be operated to pay out the winch cable 18. Initially, the counterweight 16 is lowered to the base of the tower to be supported thereon; and thereafter, further unwinding of winch cable 18 from the winch drum allows the safety appliance 21 and the lower ends of suspension cables 14 to move upwardly through the pole 11. Accordingly, the lamps 12 and fixture frame 13 will be lowered toward the ground, substantially as shown in dotted lines in FIG. 1.

Whereas there are three separate suspension cables 14, any of which is strong enough to carry the entire weight of the lamps 12 and fixture frame 13, there is little concern for the failure of one of the suspension cables 14.

However, if the winch cable 18 should fail, the lamps 12 and fixture frame 13 will fall from the top of the tower, but for the safety device 10 which includes the fixed cable 19, 20, and the safety appliance 21.

In the event the winch cable 18 fails, or breaks, the safety appliance 21 no longer will carry the tension load that it previously did when the winch cable is intact. As a result of this loss of tension load, the appliance will immediately lock against the cable 19 and be prevented from traveling upwardly in the pole 11 so as to prevent the lamps and fixture frame from falling.

More specifically, when the winch cable fails, the spring 30 will move the slide bar 29 upwardly and against whatever weight or length of anchor cable 18 remain attached to the rod so as to swing the clamp bar 32 against the cable 19 to immediately clamp the cable 19 against the jaw defined by the closed side 31.1 of the clamp body 31.

It will be recognized that the tension load normally being transmitted to each of the suspension cables 14 by the springs 28 is immediately relieved when the winch cable 18 ruptures or fails. As a result, the springs 28 tend to expand under the reduced load and move the slide rods 27 downwardly in the appliance frame.

When the appliance 21 locks onto cable 19, a tension load is once again applied to the suspension cables 14 to stop the falling of the lamps and fixture frame. The springs 28 compress again, and slightly reduce the rate of stopping of the suspension cables 14 and the fixture frame 13 as compared to the rate at which the frame of appliance 21 is stopped along the cable 19. Therefore, instead of stopping the suspension cables 14 absolutely instantaneously (as if to be stopped by a pawl against a ratchet tooth), the suspension cables and the fixture frame are stopped somewhat gradually, which has the effect of reducing the shock loading of the suspension cables and reducing the likelihood of snapping or breaking of one of the suspension cables due to extremely high rate of application of load.

Of course, the resilient yielding of springs 28 as the tension load is applied due to locking of the clamp bar 32 against cable 19 has the same effect of preventing the instantaneous and shock loading of the safety cable 19; and instead, the tension load is somewhat gradually applied to the safety cable 19 to minimize any likelihood of rupture of the safety cable 19.

It will be noted that the clamping shoe end 32.3 of the clamp bar 32 is somewhat rounded at the locations

which engage the safety cable 19, and this rounded shape of the clamping shoe 32.3 provides for at least a slight reduction in the rate of applying the tension loading to the cable 19, and a slight reduction in the rate at which the appliance 21 stops along cable 19. The clamp bar 32 must be swung by the expansion of spring 30 as the rod 29 moves through the lower frame plate 23 and this movement is required in order to rotate the clamping shoe 32.3 to the point where it will lock against the cable 19. As a result, the need for spring 30 to expand lengthwise contributes materially, along with the curvature of the clamping shoe 32.3 to reduce the shock loading or the rate of application of load to the cable 19.

It will therefore be recognized that several phases of the appliance 21 contribute to the reduction of shock loading applied to cable 19 when the appliance 21 suddenly stops, and such aspects of the appliance which contribute to this function include the spring 30 on rod 29, the curvature of the clamping shoe 32.3 and the provision of the springs 28 contributing to the resilient yieldability between the appliance frame and the suspension cables.

After the appliance 21 locks against the cable 19, the repair or replacement of the winch cable 18 may be effected. When the repair has been effected, the winch cable 18 need merely be drawn downwardly by the winch 17 to unlock the appliance 21 from cable 19. Thereafter the fixture frame may be raised and lowered as previously described.

It will be seen that I have provided a new and improved safety apparatus for a tower wherein a winch cable at the bottom of the tower is utilized for lowering and raising the suspension cables extending upwardly through the tower pole for raising and lowering the fixture frame which is normally suspended from the top of the tower. The safety apparatus includes a pair of fixed cables within the pole of the tower, and a gripping mechanism which normally transmits the tension load from the winch cable to the suspension cables. The gripping apparatus will slidably move along the safety cables provided and in response to loss of the tension load between the winch cable and the suspension cables, the safety appliance or gripping mechanism will lock against the safety cable. The gripping mechanism operates to minimize shock loading of the safety cable and of the suspension cables at the instant the safety device locks up against the safety cables and stops the falling of the fixture frame. Although the fixture frame will fall downwardly and the safety appliance 21 will move upwardly, only a few inches from the moment of failure of the winch cable to the time at which the safety appliance locks up against the safety cable, the weight of the fixture frame 13 and the lamps 12 is considerable and can produce a substantial amount of momentum which, but for the present invention, might cause a substantial shock loading of the suspension cables and possibly of the safety cable when the suspension cables are quickly locked to prevent falling of the fixture frame.

What is claimed is:

1. Safety apparatus for a tower having a fixture frame to be suspended from pulleys at the top of the tower on suspension cables and lowered by a winch cable extendible upwardly through the tower, the safety apparatus comprising:

a fixed guide cable extending from top to bottom within the tower;
 a connector appliance connected to the winch cable and also to the suspension cables for transmitting tension load therebetween for supporting the fixture frame, said appliance having a frame with attachment means for securing to the suspension cables and transmitting upward force to the frame; said appliance also including
 an upright cable-guiding jaw affixed on the appliance frame and lying along the guide cable; 10
 a clamp bar pivoted on the appliance frame adjacent said upright jaw, one end of the bar forming a clamping shoe confronting the upright jaw and cooperating therewith to guide and clamp the cable therebetween, the clamping shoe being swingable upwardly and away from the jaw to release the cable, and said shoe being swingable inwardly against the cable to clamp the cable against the jaw; 15
 a fitting connected to the other end of the clamp bar opposite the clamping shoe, and also secured to the winch cable and transmitting downward force to the bar to hold the clamping shoe out of locking relation with the guide cable; and
 a compression spring anchored on the appliance frame and urging said other end of the clamp bar upwardly to swing the clamp bar and urge the clamping shoe against and into clamping engagement with the guide cable and jaw in the event of failure of the winch cable.

2. The safety apparatus according to claim 1 and including a rigid cable guide affixed on the frame and defining an upright cable passage receiving the guide cable therethrough, said cable guide defining said cable-guiding jaw at one side of the passage and also defining a transversely opening slot across from said jaw and receiving the clamping shoe of the clamp bar therein.

3. The safety apparatus according to claim 1 wherein said fitting includes a rod extending downwardly from the clamp bar and slidably through an opening in the frame and attached to the winch cable below the frame, the spring encompassing the rod and bearing downwardly against the frame at the periphery of the opening to urge the rod and clamp bar upwardly upon failure of the winch cable.

4. The safety apparatus according to claim 1 and said attachment means includes a spring interposed between the frame and each of the suspension cables to facilitate limited motion between the appliance frame and the suspension cables to minimize the shock effect of quickly stopping the appliance along the affixed guide cable.

5. The safety apparatus according to claim 4 wherein said attachment means includes a plurality of upright attachment rods each slidably extending through an opening in the frame and connected to a respective suspension cable above the frame and each of the rods having a compression spring encompassing the rod below the respective opening in the frame, one end of each spring bearing upwardly against the frame at the periphery of the opening and the other end of the spring urging the rod downwardly to allow limited resilient movement between the frame and suspension cable in response to rapid starting and stopping of relative vertical movement between the frame and suspension cable.

6. The safety apparatus according to claim 1 and a second fixed guide cable extending from top to bottom within the tower, the appliance frame having guide means receiving and guiding along said second cable and preventing turning of the appliance in the tower as the appliance is alternately retained against upright movement by the winch cable or first-mentioned guide cable.

7. Safety apparatus to prevent falling of a tower-mounted fixture frame suspended on suspension cables trained over pulleys at the top of the tower in the event of failure of the winch cable which normally anchors the suspension cables against uncontrolled rapid travel upwardly through the tower, said safety apparatus comprising:

a pair of fixed guide cables extending from top to bottom within the tower;
 a connector appliance connected to the winch cable and also to the suspension cables for transmitting tension load therebetween for supporting the fixture frame, said appliance including
 a pair of spaced rigid frame plates above and below each other in confronting relation, and a plurality of rigid posts affixed to and interconnecting said frame plates, said frame plates having bearing apertures slidably receiving the guide cables therethrough and in side by side relation to each other;

30 a rigid U-shaped clamp body defining a cable-guiding passage therethrough and along the closed side of the U-shape, said clamp body being affixed to the frame plates with said cable-guiding passage aligned with a pair of the bearing apertures and in embracing relation with one of the guide cables, said clamp body defining a clamping jaw adjacent said passage and at the closed side of the U-shape;

40 a clamp bar with a cable clamping shoe on one end thereof and extending transversely through to the open side of said U-shaped clamp body and into proximity with the guide cable in said passage, said bar and clamping shoe extending obliquely upwardly toward the guiding cable and normally permitting free sliding between the cable and the jaw and shoe, said clamp bar being pivoted to said U-shaped body to permit upward swinging of the clamping shoe away from the guide cable and downward swinging of the clamping shoe toward and into locking engagement with the guide cable to prevent upward movement of the clamp body and connector appliance along the guide cable, said clamp bar also having an attachment end opposite the clamping shoe;

45 a slide bar depending from the attachment end of the clamp bar and connected thereto, said slide bar extending downwardly through an opening in the lower frame plate of the appliance and being slidably therethrough and said slide bar being connected to the depending winch cable;

50 a compression spring encompassing said slide bar and bearing downwardly against the frame plate at the periphery of the opening therein and also bearing upwardly on the slide bar to urge the slide bar upwardly and the clamping shoe inwardly into locking relation with the guide cable in the event of rupture of the anchor cable; and

a plurality of sliding connector rods slidably extending through openings in the upper frame plate, each of said connector rods extending upwardly from the frame plate and being connected to a respective suspension cable and also having a portion extending downwardly from the upper frame plate and embraced by a compression spring bearing upwardly against the frame plate and downwardly against the connector rod for providing resilient yieldability in the connection between the suspension cables in the appliance frame.

8. The safety apparatus according to claim 7 wherein the openings in the upper frame plate and the slidable connector rods extending therethrough are symmetrically and uniformly spaced from each other around the periphery of the upper frame plate, and the opening in the lower frame plate and the slide bar therein are disposed substantially centrally of the lower frame plate.

9. Safety apparatus to prevent falling of a tower-mounted fixture frame suspended on suspension cables trained over pulleys at the top of the tower in the event of failure of the winch cable which normally anchors

the suspension cables against uncontrolled rapid travel upward through the tower, said safety apparatus comprising a safety cable extending from top to bottom within the tower; and

a gripping mechanism loosely embracing said safety cable and slideable therealong, said gripping mechanism being connected to the suspension cables and also to the winch cable and transmitting the tension load therebetween, said gripping mechanism having releasable gripping means to tightly grip and lock onto the safety cable and also having tension load-responsive operating means resiliently biased to normally cause the gripping means to lock onto the safety cable and said tension load-responsive operating means also connected to the winch cable and operated in response to high tension on the winch cable to hold the gripping means in released condition relative to the safety cable and in response to loss of such tension load to allow said locking of the gripping means and prevent upward travel of the gripping mechanism and suspension cables in the tower.
